(57) **CLAIM**

The ornamental design for a user interface for a display screen, as shown and described.

DESCRIPTION

FIG. 1 is a front view of a user interface for a display screen showing my new design; and,

FIG. 2 is an enlarged front view thereof, the user interface is shown separately for clarity of illustration.

The broken line showing of the display screen in FIG. 1 and the elements in FIGS. 1 and 2 forms no part of the claimed design.
